UNITED STATES PATENT OFFICE.

EDWARD THOMAS, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,314,616.

Specification of Letters Patent.

Patented Sept. 2, 1919.

Application filed November 16, 1917. Serial No. 202,284.

To all whom it may concern:

Be it known that I, EDWARD THOMAS, a citizen of the United States, residing in New York city, in the county of New York and 5 State of New York, have invented certain new and Useful Improvements in Type-Writing Machines, of which the following is a specification.

This invention relates to an improvement 10 in typewriting machines, and more particularly to a collating device for assisting in assembling work-sheets on the platen.

Above the platen on the carriage or platen frame there is mounted a collating-board 15 or table on which the several work-sheets may be assembled in various relative positions. This collating-board is supported so that it can be shifted from a collating position to a delivering position such that the 20 assembled work-sheets thereon can be transferred to the platen. The collating-board is pivotally mounted for this purpose, so that after the sheets have been assembled the lower ends thereof can be swung and 25 then slid down in front of the platen between the paper-apron, the front rolls and the platen, thereby permitting the work-sheets on the collating-board to be backwardly inserted in a pack around the platen, 30 to be gripped by the platen and feed rolls before withdrawal from the impaling pins.

Other features and advantages will hereinafter appear.

In the accompanying drawings,

35 Figure 1 is a vertical section taken from front to rear, showing the collating-board in its raised position, in which position the work-sheets are assembled thereon.

Fig. 2 is a view similar to Fig. 1, except 40 that the collating-board has been swung down to deliver the assembled sheets to the platen.

Fig. 3 is a spread perspective view, showing details of an adjustable connection between the collating-board and its supporting brackets.

Fig. 4 is a detail section through the collating-board on the line 4—4 of Fig. 5, showing the mounting of the impaling studs 50 and supporting frame therefor.

Fig. 5 is a perspective view, showing the collating-board in its assembling position.

The platen 1 is mounted to rotate on a platen frame 2, which is mounted, in turn, 55 on the usual typewriter carriage. The platen

1 is rotated either by hand-knobs 3 or line-space mechanism, indicated in general at 4. To assist the platen in feeding work-sheets and for maintaining work-sheets smooth on the platen, there are provided pressure feed 60 rolls 5, which are normally held in engagement with the platen 1. These pressure feed rolls 5 are in sections and in pairs, so as to engage the platen at several points along the length thereof and at two lines at different points in a circumferential direction. The pressure feed rolls 5 are mounted on shafts 6, which, in turn, are supported by crossed bell-crank 65 7 and 8. The bell-crank 7 and 8 are pivotally mounted at 9 and are provided with arms 10 and 11, which normally engage the indented sides 12 of a rock shaft 13. When the rock shaft 13 is rotated to force the arms 10 and 11 out on the circumference of the rock shaft, the rolls 75 5 are moved out of engagement with the platen 1 and the work-sheet carried thereby. This either releases the work-sheets, so that they can be easily removed from the platen or permits the insertion of fresh work-sheets 80 on the platen. This is the usual Underwood pressure feed roll mechanism, and the shaft 13 is operated from a release key 14, which is connected to rock the shaft 13 by means of a link 15 and an arm 16 provided on 85 the rock shaft 13.

In an ordinary typewriting operation, the work-sheets are fed to the platen 1 at the rear of the same, and are guided to the bite of the platen by a work-table or plate 17. 90 The work-sheets coming from the plate 17, according to the present invention, are directed around the platen 1 with the assistance of the pressure feed rolls 5, by means of a paper-apron 18, which may comprise sections 18^a joined to each other at 18^b. The pressure feed rolls 5 extend through openings between said sections and bear against the platen 1 or the work-sheets carried by the platen. The paper-apron 18 is connected to move with the pressure feed rolls 5 95 toward and from the platen 1, by having one of the shafts 6 extend through loops or bends 19 provided in the paper-apron 18. Since the paper-apron 18 is pivotally connected at 20 to the plate 17, it may thus move toward and from the platen 1 with the movement of the pressure feed rolls 5. In the meantime, the platen may have been 100 raised by means of the case-shift key (not 105 110

shown), thus freeing the platen from the usual wing-scales. The work-sheets can thus be inserted easily on the platen 1. Also, because of the fact that the end sections 5 of the apron 18 extend up a considerable distance at the front of the platen, the work-sheets may be inserted at the front almost as readily as at the back of the platen when the apron is moved away from the platen.

For the purpose of assembling a plurality of work-sheets with interleaved carbon sheets in various relative positions before inserting them on the platen 1, there is provided 15 a collating-board or table 21 mounted on the platen frame 2, so as to travel with the platen. There are provided on the sides of the platen frame 2 supporting brackets 22. These supporting brackets 22 preferably have slots 23 to afford adjustability 20 for height between the brackets 22 and brackets 24 provided on the collating-table 21. The table 21 may pivot relatively to the brackets 22, so as to swing from the 25 collating position of Fig. 1 to the delivering position of Fig. 2. The adjustable connection may also permit the locking of the table at different levels to locate the table at different distances from the platen 1.

Mounted in each slot 23, there is a slide 25, which has its greatest length in the direction of the length of the slot 23, so as to prevent its turning in the slot. The slide 25 is provided with a hub 26, which forms 30 a mounting for an arm 27 rigidly secured to the slide, and a journal for one of the brackets 24, through an opening 28 in which the hub 26 extends. The slide 25 is provided with a screw 29 formed thereon, 35 which is engaged by a set-screw or nut 30. The nut 30 can be tightened to hold the slide 25 in any adjusted position along the slot 23, so as to selectively determine the height at which the table 21 is located. On 40 the opposite side from the screw 29 of each bracket 22, one of the brackets 24 is pivotally mounted on the hub 26 and maintained thereon by means of a nut 31, which threads onto a screw-bolt 32 formed on the 45 slide 25 beyond the hub 26. There is provided one of these combined connections having fixed position-determining adjustments and working movements on each side of the table 21.

There is also provided one of the arms 55 27 at each side of the table 21. These arms support a rod 33, which forms part of a locking means holding the table 21 in a collating position. This locking means includes a pair of latches 34, which are provided 60 with sockets 35 engaging pins 37 provided on the table-brackets 24. Both of the latches 34 are secured to the rod 33 to rotate with the same, and the latches are 65 held in their active position by one or two

springs 39, each of which engages a latch 34 at one end and an arm 27 at the other end. The limit of movement of the latches is determined by a stop-pin 36. One of the latches 34 may be provided with a finger-piece 40, whereby both of the latches may be released simultaneously. The latches 34 move up and down with the table 21 when its elevation is semi-permanently changed, and act also as brackets when the table 21 is in a collating position, preventing unsteady movement.

For the purpose of holding the work-sheets as they are assembled on the collating-board 21 and until they are delivered to the platen 1, there are provided impaling studs 41, which may engage perforations 42 in the work-sheets 43. The studs are arranged in one or more series on a sliding frame 44 mounted on the table 21. This frame 44 may be retained upon the table 21, by having the shanks of the impaling studs 41 extend into slots 45 provided in the table 21 and running lengthwise of the work-sheets 43. These studs 41 may be headed at 46, so as to engage the under side of the table 21, to prevent the studs 41 from passing through the slots 45 and thus hold the sliding frame 44 to the table 21.

One or more handles or knobs 47 may be provided on the sliding frame 44 to permit it to be easily moved along the swiveled table 21. The frame 44 is held in its normal position by a spring detent 48, Fig. 1, which engages a notch provided on the under side 100 of the slide 44, the table 21 being provided with an opening to permit access of the detent 48 to the slide 44. After a delivery, the table 21 is returned to its normal position corresponding to Fig. 1, preferably by 105 hand, but a spring may be used, against the tension of which the table may be rocked to the Fig. 2 position. The limit of the downward swing of the table 21 is determined by one or more stops 50. Indicators 110 51 are provided to show the upper limit beyond which the bottom edges of the work-sheets must not go in collating, in order to have the work-sheets gripped by the platen and rolls 5 when delivered thereto while 115 still on the frame 44.

In operation, the table 21 is adjusted to the height desired, either to accommodate work-sheets of certain length or to suit the convenience of the operative, and locked at 120 this height by tightening the nut 30. The latches 34 move with the slides 25 and thus with the table 21 for different elevations of the latter and act as brackets as well as locking means. As the arms 27 are secured 125 to the slides 25 they act on the opposite sides of the brackets 22 to the nuts 30, so that the pivotal movement of the brackets 24 relative to the hubs 26, and thus relative to the slides 25, is not impeded. The col- 130

- lating-table 21 is held in the normal inclined position of Fig. 1 by means of the latches 34, and the impaling sliding frame 44 is held in the upper position, also shown in Fig. 1, by means of the detent 48. The work-sheets may be assembled one by one with the interleaved carbon sheets and held in their assembled position by impaling them on certain of the impaling studs 41.
- 10 The impaling studs 41 used must be the ones which will bring the bottom edges of the work-sheets at least down to the indicators 51; otherwise the work-sheets when delivered to the platen will not reach the bite between the front roller 5 and the platen 1.

When all of the work-sheets have been collated upon the table 21 in the various relative positions necessary to bring certain desired lines on the several sheets into register with one another, then the table 21 may be swung down to the Fig. 2 position after releasing the latches 34. In this position it will be ready to deliver the work-sheets to the platen 1. The pressure rolls 5 and the paper-apron 18 are moved away from the platen 1 either before or after this is done, to enable the work-sheets to be inserted on the platen at the front thereof.

20 The slide 44 having thereon the impaling studs 41, and thus carrying the work-sheets, can be slid down from the Fig. 1 position to the Fig. 2 position, so that the bottom edges of the work-sheets will enter the opening 49, between the paper-apron 18, the rolls 5 and the platen 1. By inserting the finger in a groove 49^a, the work-sheets, when they are short, may then be stripped from the impaling studs 41; and

25 the feed rolls 5, together with the paper-apron 18, may be brought up against the platen 1, so that the work-sheets will be gripped to the platen. The platen may then be reversely rotated to bring the initial line of writing, which is superposed on the several sheets, to the printing point.

After inserting the work-sheets, around the platen, the collating-table is raised to the position corresponding to that of Fig. 1, in which position it is caught and locked by the latches 34. The slide 44 can be returned to its normal upper position, ready for the collating of a new set of work-sheets.

55 Variations may be resorted to within the scope of the invention, and portions of the improvements may be used without others.

Having thus described my invention, I claim:

- 60 1. The combination with a revoluble platen, of a collating table on which a plurality of sheets may be assembled preparatory to their insertion on the platen, and a swivel mounting for said table, enabling said table to be swung from a collating po-

sition with its front edge raised to a delivering position with its front edge depressed to a position adjacent the front of the platen, whereby work-sheets assembled on said table may be inserted on said platen at the 70 front thereof.

2. The combination with a platen, of a paper apron for said platen extending up in front of said platen, means for shifting said paper apron from a normal typewriting position close to said platen to a guiding position spread somewhat from said platen to enable work-sheets to be inserted at the front of said platen, and a collating table mounted to travel with said platen and 75 adjustably mounted to swing from a collating position with its delivering end spread wide apart from said paper apron to a delivering position with its delivering end near said paper apron at the front of said platen, 80 so as to direct a set of work-sheets assembled on said table to said paper apron and thus reversely around said platen in their assembled condition.

3. The combination with a platen, of a collating table for assembling work-sheets to be placed upon said platen, a variable adjustable mounting for said collating table, enabling said collating table to be elevated to different collating levels, said mounting 90 including means for permitting a swinging movement of said table from a work-sheet collating position to a work-sheet delivering position, and outside latches for holding said table in a collating position movable with 95 said table to different positions of adjustment.

4. The combination with a platen, of a collating table for said platen, and a mounting for said table between said platen and 105 said table, enabling a delivering movement of said table toward said platen for the purpose of transferring work-sheets to said platen, and also enabling a bodily relative movement between said table and said platen 110 to accommodate sheets of different lengths, so that their lower edges may come in proper contact with said platen when said sheets are transferred from said table to said platen.

5. The combination with a platen, of brackets mounted to travel with said platen in a letter-feeding direction, a collating table for assembling work-sheets to be placed upon said platen, and means for semi-permanently securing said table on said brackets at any one of several different distances from said platen, permitting a shifting movement of said table with respect to said platen for placing work-sheets as collated on 125 said platen.

6. The combination with a platen, of brackets mounted to travel with said platen, a collating table for assembling work-sheets for said platen, slides having adjustable 130

- connections with said brackets for determining the working level of said table, and a pivotal connection with said table to permit a delivering movement of said table toward 5 said platen.
7. The combination with a platen, of brackets mounted to travel with said platen, a collating table for assembling work-sheets for said platen, slides having adjustable 10 connections with said brackets for determining the working level of said table, a pivotal connection with said table to permit a delivering movement of said table toward said platen, and locking means for holding 15 said slides in any position selected, corresponding to the working level desired of said table.
8. The combination with a platen, of brackets mounted to travel with said platen, 20 said brackets having slots therein, slides in said slots, set screws for securing said slides in adjusted positions along said slots, and a collating table pivotally mounted on said slides, whereby said table may move from a 25 collating position to a delivering position with respect to said platen, and also whereby said collating table may be bodily adjusted relatively to said platen by a movement of said slides in said slots.
9. The combination with a platen, of a 30 collating table mounted to move from a collating position to a delivering position with respect to said platen, and a work-sheet attaching frame adjustably mounted on said 35 collating table to move from a collating position when said table is in a collating position to a delivering position when said table is in a delivering position.
10. The combination with a platen, of a 40 collating table pivotally mounted with respect to said platen, so as to move from a collating position to a delivering position, and a work-sheet impaling frame slidably mounted on said collating table, so as to 45 move from a collating position maintaining the work-sheets on said table to a delivering position when said collating table is in a delivering position, projecting the edges of the work-sheets from said table onto and 50 around said platen.
11. The combination with a platen, of a 55 collating table movably mounted with respect to said platen, a work-sheet attaching frame slidably mounted on said collating table, and impaling studs on said frame for holding work-sheets on said frame and on 60 said table, said impaling studs having a tongue - and - groove-sliding connection with said table to enable an adjustable movement of said work-sheet attaching frame on said table.
12. The combination with a revoluble 65 platen, of a collating board surmounting the platen and comprising two parts for both rocking to present the front end of the
- board to the front of the platen and also descending edgewise to introduce the collated sheets between the platen and the feeding devices.
13. The combination with a revoluble 70 platen, of a collating board comprising sheet-carrying means movable downwardly to introduce sheets between the platen and the feed rolls at the front of the platen.
14. The combination with a revoluble 75 platen, of a cumbent collating board swiveled above the platen to swing its front end down to the front of the platen.
15. The combination with a platen, of a 80 pin-carrying slide, a guide for said slide adapted to carry work-sheets impaled upon the pins down in front of the platen when the slide is drawn downwardly, and feed rolls below the printing point on the platen adapted to seize the work-sheets against the 85 platen.
16. The combination with a revoluble 90 platen and a platen frame, of a collating board surmounting said platen and swiveled to swing from a cumbent position to an upright position with its front edge lowermost at the front of the platen, and means upon 95 said board to collate sheets thereon.
17. The combination with a revoluble 100 platen and a platen frame, of a sheet carrier having impaling studs thereon and mounted above the platen for a swinging movement between cumbent and upright positions and for a descending movement to introduce sheets bottom foremost around the platen.
18. The combination with a revoluble 105 platen and paper-feeding devices, of a stud carrier above said platen for carrying collated sheets, and means whereon said stud carrier is mounted to permit it to swing from a cumbent to an upright position, and also to descend to carry the collated sheets down between the platen and the paper-feeding devices.
19. The combination with a revoluble 110 platen and paper-feeding devices, of a collating board surmounting the platen and swiveled to swing its forward edge downwardly to the front of the platen, a slide 115 mounted upon said collating board, and collating pins upon said slide, said slide movable downwardly along said collating board to introduce sheets between the platen and the feeding devices.
20. The combination with a revoluble 120 platen and paper-feeding devices, of a collating board surmounting the platen and swiveled to swing its forward edge downwardly to the front of the platen, a slide 125 mounted upon said collating board, collating pins upon said slide, said slide movable downwardly along said collating board to introduce sheets between the platen and the feeding devices, said slide comprising two 130

studded plates, one at each side of the table, and a bar connecting said plates.

21. The combination with a revoluble platen, of a paper roll to run on the under side thereof, a paper-guiding apron extending forwardly under the platen toward the front thereof, means to release said roll and automatically carry the upper part of said apron away from the platen to facilitate the entrance of sheets at the front of the platen, a pin-carrying slide, and a guide for said slide adapted to carry work-sheets impaled on the pins down in front of the platen when the slide is drawn downwardly until 15 the work-sheets are seized by the roll.

22. The combination with a revoluble platen, of a paper roll to run on the under side thereof, a paper-guiding apron extending forwardly under the platen toward the front thereof, means to release said roll and automatically carry the upper part of said apron away from the platen to facilitate the entrance of sheets at the front of the platen, and means to drop sheets between the platen 20 and said apron and roll.

23. The combination with a revoluble platen, of a paper roll to run on the under side thereof, a paper-guiding apron extending forwardly under the platen toward the front thereof, means to release said roll and automatically carry the upper part of said apron away from the platen to facilitate the entrance of sheets at the front of the platen, and means to collate sheets above the platen 30 and drop them while collated down between the platen and said apron and roll.

24. The combination with a revoluble platen and paper-feeding devices, of a collating board surmounting the platen and comprising two parts, both of said parts rocking 40 to present the front end of the board to the front of the platen and one of said parts descending edgewise to introduce the collated sheets between the platen and the feeding devices, and a latch to hold said collating board in normal position.

25. The combination with a revoluble platen and feed rolls, of a collating-board surmounting the platen, said collating-board 50 being pivotally-supported and swingable

from a collating position, to introduce collated sheets between the platen and the feed rolls.

26. The combination with a revoluble platen and feed rolls, of a collating-board 55 comprising sheet-inserting means, said collating-board being pivotally-supported above said platen and swingable from a collating position, to introduce collated sheets between the platen and the feed rolls by 60 said sheet-inserting means.

27. The combination with a revoluble platen and feed rolls, of a collating-board 65 surmounting the platen, and having an inclined normal position for the purpose of collating work-sheets, said collating-board being rockable from said collating position to a substantially vertical position, and means for introducing the collated work-sheets between the platen and the feed rolls 70 when said table is in the latter position.

28. The combination with a revoluble platen and feed rolls, of a collating-board 75 surmounting the platen, said collating-board being rockable from a collating position, means for introducing the collated work-sheets between the platen and the feed rolls, and a limit-indicator, to which or beyond which the ends of the work-sheets should always extend. 80

29. The combination with a platen, of feed rolls, a shaft on which said feed rolls are mounted, a pivoted paper-apron for said platen, said apron being connected to said feed-roll shaft, means for simultaneously releasing said feed rolls and shifting said paper-apron from a normal typewriting position close to said platen, to enable work-sheets to be inserted at the front of said platen, and a collating-table mounted to 85 swing from a collating position to a delivering position with its delivering end near said paper-apron at the front of said platen, so that work-sheets may be inserted between said apron and said platen. 90

EDWARD THOMAS.
